UNITED STATES PATENT OFFICE.

PERCY H. YOUNG, OF DORCHESTER, MASSACHUSETTS, ASSIGNOR TO S. A. WOODS
MACHINE COMPANY, OF BOSTON, MASSACHUSETTS, A CORPORATION OF MASSA-
CHUSETTS.

WOODWORKING MACHINE.

1,407,112.

Specification of Letters Patent. Patented Feb. 21, 1922.

Application filed March 17, 1921. Serial No. 452,928.

To all whom it may concern:

Be it known that I, PERCY H. YOUNG, a citizen of the United States, and a resident of Dorchester, county of Suffolk, and State 5 of Massachusetts, have invented an Improvement in Woodworking Machines, of which the following description, in connection with the accompanying drawings, is a specification, like characters on the drawings 10 representing like parts.

This invention relates to wood working machines and in particular to the construction of the side leg and associated mechanism of a matcher or profiler, that is, to the 15 cutter mechanism mounted on a more or less upright axis to operate on the edge of a board passing through the machine.

The improvements constituting my invention will be best understood by the following description of the mechanism shown in the accompanying drawings, wherein I show by way of example illustrative embodiments 20 of my improvements, and wherein:

Fig. 1 is a plan view of that portion of 25 a matcher adjacent the side heads;

Fig. 2 is a side view with parts in section;

Fig. 3 is a section on the line 3—3 of 30 Fig. 1 with one of the side legs in a different position of adjustment;

Fig. 4 is an elevation of one of the side legs and the carriage carrying the same, the point of view being from the side opposite that of Fig. 3 or from the right in Fig. 35 2; and

Fig. 5 is a section on the line 5—5 of Fig. 4.

Referring to the drawings and particularly Figs. 1 and 2, I have there shown a 40 machine having two staggered side legs 6 and 8 operating on opposite sides of a board B passing through the machine on the work supporting surfaces 10 provided on the framework of the machine. In the example 45 shown, each of the side legs as 6 comprises a rotary cutter head 12 directly driven by an electric motor 14. The side legs are so arranged that they may be adjusted transversely of the machine to operate on boards 50 of different widths and may also be adjusted angularly as indicated in Fig. 3 to operate on a bevel or otherwise to provide a suitable profile for the edge of the board in accordance with the design of the cutters on the 55 head 12.

In the form of the invention shown the side leg is mounted for both pivotal and translative adjustment and means are provided for clamping it alternatively against either one of these movements and a single 60 adjusting mechanism accessible at the side of the machine will cause the side leg to be adjusted either angularly or laterally accordingly as one or the other of the cooperating clamping devices is in use. This subject 65 matter broadly is not my invention and is claimed in an application of Louis T. Medholdt of Winthrop, Massachusetts. The particular mechanism here shown and various features of construction are original with me and the features of novelty which I claim as my invention will be more particularly pointed out in the appended claims.

To provide for the various movements of the side leg, the motor casing 14, as best 70 shown in Fig. 2, may be mounted on a carrier plate 16 on which it may, if desired, be vertically adjusted by mechanism 18 of well known type. The carrier 16 is mounted, conveniently in the manner hereinafter described, on a carriage 20 adapted to slide 75 transversely of the machine on a guideway 22. Movement of the carriage on the guideway will effect an in and out adjustment of the side leg. To permit swinging adjustment of the side leg it is mounted pivotally on the carriage 20 and an important feature of my invention consists in the mounting of a side leg of a matcher or like machine in such a manner that it may be angularly ad- 80 justed about a center located in the plane of the work support as 10. By such a construction the cutter head may be adjusted angularly in desired manner to operate on the edge of the board without the necessity for vertical or other adjustment as the angle 85 is changed.

Referring more particularly to Fig. 3, the carrier 16 is here mounted on the carriage 20 to swing about a point 24 as a center, 90 which point is located substantially at the intersection of the plane defined by the work support 10 and the plane tangent to the cutter head interiorly thereof and in which the cutting operation is performed. It will be 95 understood that this point 24 may move horizontally, viewing Fig. 3, in accordance with the in and out adjustment of the side leg. Herein the carriage 20 is provided with an arc shaped rib 26 centered at the 100 110

point 24 with which cooperates a downwardly facing hook shaped rib 28, best shown in Figs. 2 and 5, by which the carrier 16 is suspended on the carriage 20 in such 5 a manner that it may swing thereon about the point 24 as a center as 28 is moved along 26.

Suitable means are provided whereby the side leg may be held either against swinging 10 movement or in and out translative movement. Referring to Figs. 2 and 4 I will first describe the means whereby the carrier plate 16 is clamped to the carriage 20 to prevent rotative movement. I have here shown a 15 screw 30 tapped into plate 16 and loosely receiving a chock block 32 presented adjacent an edge of the carriage 16, set screws 34 being provided for positioning the block. Mounted on the screw 30 is a cam 36 provided 20 with a hand lever 38 whereby screw and cam can be rotated in such a manner as to press the chock 32 inwardly against the margin of the carriage 20 as in Fig. 2 whereby to clamp the carrier 16 and consequently 25 the side leg so that the side leg will move with the carriage as a unit and not be capable of rotative movement relatively thereto. For locking the carriage 20 to the guide 22 to preclude translative movement of the 30 side head I may provide a locking rod 40 (best shown in Figs. 2 and 4) having a squared end extending from the side of the machine by which it may be turned, this locking rod being received between the 35 lower margin of the guideway 22 and the opposed surface of a bracket 42 which extends rearwardly from the carriage 20, the rod being held in position by a clip 44 as illustrated. The rod has one side flattened 40 or slabbed off as shown at 46 in Fig. 4 and cooperating therewith is an adjusting screw 48 tapped through the bracket 42. When the flattened surface of the rod is interposed between the guideway 22 and the end of 45 screw 48 there is freedom of movement between the carriage 20 and the guideway. When, however, the rod is turned to bring the full diameter thereof between the parts, it serves to jam the two together so that the 50 carriage is locked on the guideway and must move as one therewith.

A single adjusting mechanism is provided which will serve either to move the side leg in and out or to swing it accordingly as 55 whether one or the other of the cooperating clamping mechanisms is in use. For this purpose a suitable traversing means such as an adjusting screw is connected to the side leg itself at a point remote from the pivot. 60 This idea, as I have pointed out, is broadly not original with me but the mechanism here shown including the clamping elements are my invention. It will be clearly understood that if the side leg is held against transla-

tive movement it is free to swing about point 65 24 and movement of the adjusting device will cause it to swing about its pivot. If, on the other hand, such pivotal movement is prevented, the same force will tend to move the leg bodily. The device in the present 70 instance takes the form of a screw 50 journalled in the frame of the machine and having an operating portion such as the squared end shown projecting at the side thereof. The mechanism is best shown in Figs. 4 and 75 5 where there is illustrated cooperating with the screw a nut 52 which is mounted to slide in an undercut guide 54 in the carriage 20 and has projecting therefrom a pin 56 extending from the face of the carriage and 80 entering a radial slot 58 in the carrier plate 16, the slot 58 being radial to the center 24 and thus transverse, as shown in Fig. 2, to the guideway 54 which receives the nut. Referring to Fig. 2, if we assume the clamping bar 40 to be in position to lock the carriage 20 on the guide 22 and the clamping chock 36 to be released, permitting the carrier 16 to swing on the carriage 20 about the 85 arcuate support 26, if the adjusting screw 50 is then turned the nut 52 will be moved in its guides 54, say towards the reader viewing Fig. 2, and the pin 56 acting on the walls of the slot 58 will swing the side leg to the position shown in Fig. 3. On the other hand, 90 if the clamp 40 is released and the clamp 32 thrown in, as in Fig. 2, locking of the carrier 16 to the carriage 20 will prevent the nut 52 from moving in the guideway since it will be locked by engagement of the pin 56 100 in the slot 58 as will clearly be understood from Fig. 3. Therefore, rotation of the screw 50 will move the nut and with it the carriage 20 and the side leg will be moved bodily in and out along the guideway 22. 105

This construction provides for a convenient gage or index of the angular position of the cutter since angular adjustment of the side leg is effected by movement of the nut 52 in the guides 54. Referring to Fig. 4, 110 there is carried by the nut a rod 60 projecting laterally and cooperating with an index or pointer 62 carried by the edge of the carriage 20. Suitable graduation marks on the rod 60 will give a conveniently read indication of the position of the nut 52 and consequently of the angular adjustment of the leg. Thus in a given instance the parts may be proportioned to provide for a movement of 30° on one side of the vertical and 15° on 115 the other side. The set screw 62 by which the rod 60 is secured permits proper placing of the zero point thereof.

The arrangement of the leg to swing about the center 24 facilitates the adjustment as 120 thus force applied through pin 56 works with a relatively long lever arm.

Referring to Fig. 3, a suitable bracket 64

is provided and is arranged to turn angularly with the side leg. In the present instance I have shown it as formed on the motor casing. This bracket provides a support 5 for a jointer 66 which may be brought into cooperation with the cutter head in any position of adjustment of the side leg. Thus the cutter may be sharpened at any time without disturbing its angular adjustment. 10 I believe that I am the first to provide for jointing a side head after its adjustment to angular position in this manner.

Referring to Fig. 1, I will next describe the construction of the chip breaker there 15 shown. This embodies a generally U-shaped member exteriorly embracing the side head, one arm of the U being pivoted to fixed point 68. The U is made in two portions and has the pin and slot adjustment 20 70 in the base thereof. The other leg 72 of the U forms the chip breaker proper and projects inwardly and bears against the side of the board adjacent the cutter head 12. A suitable stop 74 cooperating with the side 25 75 of the machine prevents the arm 72 from swinging in too far and from being carried into contact with the cutter head 12.

To press the chip breaker in against the work means are provided tending to swing 30 it bodily counterclockwise about the pivot 68. Herein an abutment 76 on the base of the U thrusts against a rod 78 carrying a nut 80 which works against the spring 82 interposed between this nut and the upright member 84, best shown in Fig. 2. The member 35 84 is connected by a link 86 to bracket 88 projecting from the frame of the machine and by the link 90 to the pivot pin 68, this connection being made, as shown in Fig. 1, 40 by an open hook on the link 90 for a purpose hereinafter described. Viewing Fig. 1, it will be seen that if the arm 72 of the chip breaker is pushed clockwise by the work, the whole U-shaped frame will swing 45 about the pivot 68 and the rod 78 will be thrust to the left through member 84 compressing the spring 82. The chip breaker is thus held by spring tension against the work and all the parts are very simply organized 50 around the cutter head on the top of the frame of the machine, being connected thereto by the single pivot 68 and the simple connection at the bracket 88. The upright member 84 may be provided with an 55 upwardly extending handle 92, as best shown in Fig. 2, by means of which it may be pressed to the right viewing Fig. 1, so that the link 90 may be swung free from pivot 68. The tension on the chip breaker 60 through the spring 82 is then released and the chip breaker may then be swung bodily about the pivot point 68 in a clockwise direction. The force of the spring which would otherwise resist this action is exerted

in swinging link 86 outwardly, this being 65 permitted by the disengagement of the link 90 and no substantial resistance is presented to the movement of the chip breaker.

Direct driven cutter heads of the type here shown turn very readily on their bearings and there is thus a marked tendency for them to spin after the current has been cut off from the motor. I find it convenient, therefore, to provide a simple mechanism for bringing the rotation of the heads to a 75 stop. Referring to Fig. 4, I have there shown a brake shoe 94 preferably in the form of a plug or rod of wood loosely received in a suitable opening in the motor casing and adapted to be thrust upwardly 80 against a disc 96 mounted on the rotor of the motor by means of the pivoted handle 98.

Having thus described in detail the mechanism shown in the accompanying drawings 85 as embodying for illustrative purposes the subject matter of my invention, the principles exemplified thereby which I claim as new and desire to secure by Letters Patent I shall express in the following claims. 90

Claims:

1. In a machine of the class described a transverse guideway, a carriage slidable thereon, a side leg carrier pivoted on the carriage, means to clamp together carriage and 95 guideway, means to clamp together carrier and carriage, a nut having slidable connection with the carriage and rotatable connection with the carrier and an adjusting screw 100 cooperating with the nut.

2. In a machine of the class described a transverse guideway, a carriage slidable thereon, a side leg carrier pivoted on the carriage, means to clamp together carriage and guideway, means to clamp together carrier and carriage, a nut having slidable connection with the carriage and rotatable connection with the carrier, an angle gage operated by the sliding movement of said nut and an 105 adjusting screw cooperating with the nut. 110

3. In a machine of the class described a transverse guideway, a carriage slidable thereon, a side leg carrier pivoted on the carriage, means to clamp together carriage and guideway, means to clamp together carrier 115 and carriage, a nut having slidable connection with the carriage and rotatable connection with the carrier, a graduated bar carried by the nut and an adjusting screw cooperating with the nut.

4. In a machine of the class described and comprising a mechanism to be linearly and angularly positioned, a carrier for such mechanism, a carriage on which the carrier is pivoted, a guideway for the carriage, 125 means to clamp the carriage to either carrier or guideway, a member guided for transverse movement on the carriage and

having a pin entering a radial slot in the carrier and means for exerting a force on said member tending to move it transversely.

5. In a machine of the class described a support for work passing through the machine, a side leg comprising a rotary spindle carrying a cutter head of generally cylindrical form to operate on work passing over said support, said side leg having means for 10 moving it transversely across the machine and also means for swinging it about a center located substantially in the intersection of the plane of the work support with the plane of cutting tangent to said head where- 15 by the angle of cut made by the head may be

altered without axial adjustment of the side leg.

6. A matcher or the like comprising a support for work passing through the machine and having opposed side legs comprising 20 rotary cutters of generally cylindrical form to operate on the side portions of work on said support, one of the same being pivoted for swinging movement about a center located substantially in the intersection of the 25 plane of the work support with the plane of cut tangent to said cutter.

In testimony whereof, I have signed my name to this specification.

PERCY H. YOUNG.
